UNITED STATES PATENT OFFICE

LOUIS A. GEBHARD, OF WASHINGTON, DISTRICT OF COLUMBIA, ASSIGNOR TO WIRED RADIO, INC., OF NEW YORK, N. Y., A CORPORATION OF DELAWARE

INDUCTANCE SYSTEM

Application filed June 5, 1929. Serial No. 368,691.

My invention relates broadly to inductance systems and more particularly to inductance systems employed in high frequency transmitters.

1. One of the objects of my invention is to provide an efficient adjustable inductance system.

2. Another object of my invention is to provide a plurality of interchangeable inductances adapted to be selectively placed in electrical relation with an external circuit.

3. A further object of my invention is to provide an inductance system wherein the resistance of the inductance coils is maintained substantially constant irrespective of the current therein.

4. Other and further objects of my invention reside in certain structural features I employ in the inductance system of my invention whereby the electrical efficiency of adjustable inductance systems is improved.

5. My invention will be more fully understood from the specification hereinafter following and by reference to the accompanying drawings wherein: Figure 1 shows a front elevation of the inductance system of my invention; Fig. 2 shows a part horizontal section of the inductance system of my invention on line 2—2 of Fig. 1; Fig. 3 shows a side elevation of a modification of my invention; Fig. 4 shows a part horizontal section of the modified form of my invention on line 4—4 of Fig. 3; and Fig. 5 shows an end view of a section of the inductance system of my invention on line 5—5 of Fig. 3.

6. In high frequency transmitters it is necessary to employ inductances to control the frequency of the generated energy. When ultra high frequency is employed the inductance must be of a low order. This limits the physical dimensions. As the physical dimensions are limited the safe current carrying capacity is limited. In the adjustable inductance system of my invention large values of current may be safely carried without employing an inductance of large physical dimensions. When employing adjustable inductances it is essential that the losses be reduced to a minimum. Losses resulting from unused portions of an inductance coil and in-

duction between the used and unused coils are avoided in the inductance system of my invention.

7. Figs. 1 and 2 of the drawings show a side elevation and a part section respectively of one form of the inductance system of my invention. To prevent excessive rise of temperature when the inductance system is employed in high power transmitters, I employ a cooling system which adequately maintains the inductance coils at a normal temperature.

8. Inductance coils 1, 2, 3 and 4 are mounted on insulating supports 5. Coils 1, 2, 3 and 4 comprise lengths of metallic tubing or the like wound in the helical formation illustrated. Contacts 6 are carried by each of the coils by means of which electrical connection to an external circuit is established when the respective coils are in the proper position and contacts 6 engage with brush contacts 7. Brush contacts 7 may be of any suitable spring metal mounted on an insulating bar 8. Brush contacts 7 are adapted to be adjustably positioned on bar 8 in the proper positions whereby contact will be established with the respective contact members 6 carried by coils 1, 2, 3 and 4. Coils 1, 2, 3 and 4 are of increasing inductance value in the order named. Coils 1, 2, 3 and 4 interconnected by means of lengths of insulating tubing 9. Insulating tubing coils 10 and 11 are wound around forms 12 and 13 respectively and provide a high resistance path for direct current. The fluid circulates through insulating tubing coil 11, coil 4, coil 3, coil 2, coil 1 and insulating tubing coil 10 or in reverse of the order named. The circulation is continuous through the entire inductance system. Insulating members 5, 12 and 13 mounted on tubes 14 and 15 form a part of the supporting framework for each of the coils. Tubes 14 and 15 are of slightly larger diameters than tubes 16 and 17, the former sliding over the latter and affording liquid tight connections for the circulating fluid. The upper ends of tubes 14 and 15 connect to the ends of insulating coils 11 and 10, respectively.

9. The cooling fluid may be admitted to the lower end of tube 16 and caused to circulate

through insulating coil 11, through metallic inductance coils 4, 3, 2 and 1, through insulating coil 10, through tube 15 and out of the inductance system through tube 17. The framework carrying coils 1, 2, 3 and 4 may be moved in the vertical plane selectively connecting the respective coils with external circuits. A suitable mechanical arrangement for effecting this movement is shown and 10 fully described in my co-pending application Serial No. 400,082 filed October 16, 1928. The selected inductance coil for a given frequency adjustment may be retained in contact with the external circuit by means of 15 stops 21 inserted in holes 18. Holes 18 are provided in vertical frame members 21a. Members 21a are supported by horizontally positioned members 21b and 21c.

Figs. 3, 4 and 5 illustrate front, sectional 20 and side elevations, respectively, of a modification of the adjustable inductance system of my invention. Reference characters correspond to those shown in Figs. 1 and 2. Extensions of insulating tubing coils 10 and 11 25 are shown comprising flexible loops at the points 19 and 20 respectively, when the coil system is moved in a vertical plane. Members 22 serve to guide the tubing from the framework, and are carried by member 23. Supporting members 5, 12 and 13 are of suitable 30 insulating material and are positioned on the vertical insulating members 23 and 24. The framework carrying coils 1, 2, 3 and 4 and insulating tubing coils 10 and 11 may be 35 adjusted in the vertical plane without interrupting the circulation of the cooling fluid.

Under most operating conditions it is essential that coils 1, 2, 3 and 4 be electrically 40 insulated from each other. The coupling units interconnecting the several coils may therefore comprise lengths of rubber tubing or the like which will serve the purpose.

Many modifications of my invention are 45 possible without departing from the spirit of my invention. I have referred to the movement of the inductance coils in a vertical plane. However, it is obvious that the framework may be positioned in a horizontal plane if desired and the movement of the coils governed accordingly. In radio transmitters in 50 locations where space is very limited as on shipboard, it is necessary to use every cubic inch of space to the greatest possible advantage. The inductance system of my invention is inherently compact and very advantageous for such locations. In other systems the electromagnetic induction between used and unused coils introduces serious losses. This often occurs where the distance of movement 55 necessary to effect a change of coils is greater than the distance between the axes of the coils. In the inductance system of my invention the distance between the axes of the several coils employed is the same as the distance traversed to effect a change of coils.

Thus assume a "drum" type of variable inductance system, having four cylindrical inductances symmetrically mounted on a cylindrical frame with their axes parallel to the axis of the cylindrical frame and having contact elements projecting at their outermost points. The distance between the contact elements of adjacent inductances will be equal to a quadrant of the peripheral circle of the cylindrical framework, and in practice the shortest distance between adjacent inductances will be less than half the radius of the cylindrical frame. If now it be assumed that the same two coils are mounted on a "ladder" or linear frame with the same distance as before between the contact elements of adjacent coils, the shortest distance between adjacent coils will in practice be found to be twice or more as large as with the drum type. The interaction between adjacent coils increases rapidly as the shortest distance between adjacent coils is reduced and hence the "ladder" type has inherent advantages over the "drum" type because of the reduced interaction.

I realize that many modifications of my invention are possible and it is to be understood that the embodiments of my invention are not to be restricted by the foregoing specification or by the accompanying drawings but only by such restrictions as are imposed by the appended claims.

What I claim as new and desire to secure by Letters Patent of the United States is as follows:

1. An adjustable inductance system comprising a fixed framework, a rack framework movable with respect to said fixed framework, a plurality of individual inductance coils positioned on said rack framework, fixed contact elements carried by said fixed framework, said coils comprising lengths of metallic tubing adapted to be cooled by a circulating fluid, each of said coils being provided with coil contact elements adapted to engage said fixed contact elements selectively, and said rack framework adapted to be adjusted to different positions whereby said coils are selectively connected with an external circuit.

2. An adjustable inductance system comprising in combination a fixed framework, a rack framework movable with respect to said fixed framework, a plurality of individual inductance coils spacially positioned along said rack framework, fixed contact elements carried by said fixed framework, said coils comprising individual lengths of metallic tubing physically interconnected for the circulation of a cooling fluid and electrically insulated from each other, coil contacts carried by each of said coils and adapted to selectively engage said fixed contact elements as said framework is moved, whereby said coils are selectively connected with an external circuit.

3. An adjustable inductance system comprising in combination a movable rack mem-

- ber a plurality of inductance coils each having different frequency characteristics, said coils being spacially positioned on said movable rack member, said coils comprising individual lengths of metallic tubing interconnected by fluid conducting electrical insulating members for the circulation of a cooling fluid and adapted to be selectively connected with an external circuit.
4. An adjustable inductance system comprising in combination a plurality of helically wound inductance coils of different frequency characteristics disposed in the same plane and adapted to carry large currents, said inductance coils being carried by a movable rack and having an interior channel through which cooling circulatory liquid flows.
5. An adjustable inductance system comprising in combination a plurality of inductance coils having their axes extending parallel one to another and having different frequency characteristics being positioned on a movable rack member and in substantially the same plane, said coils comprising lengths of helically wound tubing and being physically interconnected for the circulation of a cooling fluid.
6. An adjustable inductance system comprising in combination a plurality of inductance coils specially positioned with their axes in substantially the same plane and spaced one from another on a movable rack member, said coils having fluid conducting passages and said coils being physically interconnected by fluid conducting members.
7. An adjustable inductance system comprising in combination a plurality of independent electrical inductance coils, said coils comprising lengths of helically wound tubing interconnected by fluid conducting members, a rack framework carrying said coils and adapted to be adjusted in a given plane, and means for selectively effecting electrical connection between said coils and an external circuit.
8. An adjustable inductance system comprising in combination a fixed framework, a rack framework movable with respect to said fixed framework, fixed contact members carried by said fixed framework a plurality of helically wound inductance coils spacially positioned on said rack framework, said coils comprising individual lengths of metallic tubing interconnected for the circulation of a cooling fluid therethrough, independent contact members carried by said coils and means for moving said rack whereby the independent contact members on said coils are selectively connected with the fixed contact members on said framework and with an external circuit.
9. An inductance system of the ladder type, comprising a fixed frame member, a movable frame member adjustable in position with respect to said fixed frame member, a plurality of lateral co-planar members carried by said adjustable frame member, a plurality of helically wound tubular inductance elements carried respectively by said lateral members, said inductance elements being connected in electrical insulating relation for the continuous passage of liquid successively therethrough, fixed contact elements carried by said fixed frame, coil contact elements carried respectively by said coils and adapted to engage said fixed contact elements as the position of said adjustable frame is changed.
10. An inductance system of the ladder type, comprising a fixed frame member, a movable frame member adjustable in position with respect to said fixed frame member, a plurality of lateral co-planar members carried by said adjustable frame member, a plurality of helically wound tubular inductance elements carried respectively by said lateral members, said inductance elements being connected in electrical insulating relation for the continuous passage of liquid successively therethrough, flexible electrically insulating liquid conductors connecting the unconnected ends of the terminal inductance elements respectively to a source of fluid supply and a waste discharge, fixed contact elements carried by said fixed frame, and coil contact elements carried respectively by said coils and adapted to engage said fixed contact elements as the position of said adjustable frame is changed.
11. An inductance system of the ladder type comprising a fixed frame member, a movable frame member adjustable in position with respect to said fixed frame member, a plurality of lateral co-planar members carried by said adjustable frame member, a plurality of helically wound tubular inductance elements having different values of inductance carried respectively by said lateral members, said inductance elements being connected in electrical insulating relation for the continuous passage of liquid successively therethrough, fixed contact elements carried by said fixed frame, and coil contact elements carried respectively by said coils and adapted to engage said fixed contact elements as the position of said adjustable frame is changed.
12. An inductance system of the ladder type comprising a pair of fixed tubular members, a pair of movable tubular members adapted to respectively telescope over said fixed tubular members in water-tight relation, a plurality of lateral members extending between said movable tubular members, a plurality of helically wound tubular inductance elements carried respectively by said lateral members, said inductance elements being connected in electrical insulating relation for the continuous passage of liquid successively therethrough, fluid conductors connecting the unconnected ends of the ter-

minal inductance elements respectively to said movable tubular members for the passage of fluid therethrough, a source for supplying cooling liquid to one of said tubular members, means for conducting waste liquid from one of said tubular members, fixed contact elements carried by said fixed tubular members, and coil contact elements carried respectively by said coils and adapted to engage said fixed contact elements as the position of said movable tubular members is changed.

CERTIFICATE OF CORRECTION.

Patent No. 1,809,933.

Granted June 16, 1931, to

LOUIS A. GEBHARD.

It is hereby certified that error appears in the printed specification of the above numbered patent requiring correction as follows: Page 3, line 30, claim 6, for the word "specially" read spacially; and that the said Letters Patent should be read with this correction therein that the same may conform to the record of the case in the Patent Office.

Signed and sealed this 14th day of July, A. D. 1931.
